SYNCHRONIZING SYSTEM

Rudolf Urtel, Berlin, Germany, assignor to Tele-funken Gesellschaft für Drahtlose Telegraphie m. b. H., Berlin, Germany, a corporation of Germany

Application May 20, 1936, Serial No. 80,692
In Germany May 15, 1935

3 Claims. (Cl. 178—69.5)

The present invention relates to a synchronizing system, and is more specifically directed toward synchronizing systems adapted for television and facsimile systems.

In synchronizing systems of the past adapted to be used in television, all facsimile synchronizing impulses were transmitted on the same channel for both line and frame, which had the distinguishing characteristic of being of unequal duration; the shorter synchronizing impulses serving to synchronize the line formation while the longer impulses were utilized to synchronize for frame. Thus, for example, the line synchronizing pulses might have a duration equal to 10% of the time it takes to scan one line, while the frame synchronizing impulse might be equal to 10% of the time to scan one picture frame. Separation at the receiver of these synchronizing signals was accomplished by amplitude separation. For example, the amplitudes might be graduated in the following manner:

Zero antenna current would be representative of the synchronizing impulses. 50% of the maximum antenna current would represent the black portions of the picture, while maximum antenna current would represent the pure white portions of the picture. That is to say that the synchronizing signals or impulses were blacker than the blackest portion of the signals. Separation of the line synchronizing impulses and the picture or frame synchronizing impulses is accomplished by frequency selection in the following fashion:

The synchronizing signals are fed to a parallelly connected condenser and resistance of such time constant that the line synchronizing impulses of brief duration are unable to change the potential across the network appreciably, while the frame impulse of long duration is able to produce a large change in potential across the network. The change in potential is used to control thermionic tubes to produce synchronization. The result, however, of such frequency selection is that the beginning of the frame impulse, instead of being sharp is distorted. That is to say, the build-up time being appreciable changes the sharp slope of the framing impulse into one of relatively small slope. This causes blurring and imperfect and faulty synchronization. While this defect is not of such great importance in the usual standard method of scanning in which lines of one frame coincide or are in register with lines of preceding frame, the error becomes very important when interlaced scanning is used.

It is accordingly, one of the objects of my in-

vention to provide an improved synchronizing method for television and facsimile systems.

It is a further object of my invention to eliminate blurring of images due to faulty synchronizing produced by network distortions.

A further object of my invention is to provide means to correct for distortion in synchronizing signals.

A still further object of my invention is to provide a synchronizing method which will enhance the operation of television and synchronizing systems utilizing interlaced scanning.

Other objects and advantages of my invention will be readily apparent to those skilled in the art upon reading the following description of my invention taken in conjunction with the drawing.

Referring now to the drawing:

Figs. 1a and 1b are representative of interlaced scanning patterns;

Figs. 2a, 2b, 2c, 2d, 2e, and 2f are representative of the types of synchronizing signals received after being distorted and finally reshaped by applicant's invention; and

Fig. 3 shows one embodiment of applicant's invention for overcoming distortion in the synchronizing signals.

Where interlaced scanning is used, the lines of one picture must fit exactly on the gap of the preceding picture, as shown in Fig. 1a. Slight deviations make the pairing of the lines apparent and this means a coarse structure of the image, as clearly illustrated in Fig. 1b where a departure of only 10 percent has been assumed for the line interval. By such line pairing in the scanning of the picture there results a picture scan equal to one-half the normal number of lines.

According to this invention a better time definition of the picture is to be obtained in television. The invention, of course, may in a similar way be used in other fields. The picture impulse is so made that it is resolved into a "preparatory or announcement order" and "an execution order." During the re-creation of the picture, the frame synchronizing device is entirely blocked so that the impulses cannot affect the picture reproduction. Frequency selection, which, as above pointed out, entails impulse blurring or distortion, will now be needed only for the preparatory impulse in order to make the picture change means ready. Next the execution or performance impulse which is not routed through a filter causes the actual change of picture so that there will be a sharply defined initiation and beginning.

Figs. 2a to 2f illustrate in more detail the behavior of the impulse sequence. Along the abscissa is the time axis. Fig. 2a shows a series of line synchronizing impulses which is interrupted by a longer picture synchronizing impulse of the same amplitude. Fig. 2b shows the distortion suffered by this impulse series while passing through the filter. The line impulses which do not cause any noticeable voltage variation across the suitably chosen parallelly connected resistance and capacity network are followed by the picture impulse which is badly mutilated at the point marked *r*. As a consequence, the time definition of the picture change is extremely faulty. In a similar way, Figs. 2c and 2d illustrate the distortion occurring in another type of signalling where a long impulse is transmitted instead of a long spacing period.

Using the same mode of illustration as in Figs. 2a-2d, Figs. 2e and 2f illustrate the structure of the picture synchronizing impulse consisting of the announcement or preparatory signal *a* and the execution signal *b*.

A circuit organization adapted to carry the basic idea of the invention into practice is illustrated in Fig. 3. In this figure a thermionic discharge tube I, having a control electrode, plate and cathode, has its plate connected to the positive pole of a voltage supply 7. Connected in series with the negative pole of the voltage supply and the cathode of tube I is a filter comprising a resistance 3 and a condenser 5. Input terminals 15 are connected to the control electrode of tube I and to the cathode of the tube. A gaseous discharge tube II has its cathode connected to the cathode of tube I. The control electrode of tube II is connected through a condenser 11 to the control electrode of tube I. The anode of the tube II is connected to one side of the load circuit, while a voltage supply 9 has its positive pole connected to the other side of the load, while its negative pole is connected back to the common cathode connection. A serially connected resistance and biasing source E_g is connected to the control electrode of the tube II and to the junction point of the negative pole of the voltage source 7 and the filter comprising the resistance 3 and condenser 5, so that the tube II is negatively biased, and being of the gaseous discharge type, is normally in such a condition that no current flows through the plate circuit of the tube and the load L. It will thus be evident that the control electrode of the tube II has its control electrode potential determined by the value of the biased battery E_g and the potential drop across the filter comprising the resistance 3 and the condenser 5. The potential across the filter is, of course, determined by the current flowing through the plate circuit of the tube I, which, in turn, is determined by the impulses fed to

the terminals 15. The impulses are fed to tube I. Across the resistance of filter 3-5 is caused to arise a potential which so biases the grid of the gaseous discharge tube II that the impulses will leave tube II unaffected. Lacking line impulses (announcement or preparatory signals) permit the potential at the filter 3-5 to decay so that, while auxiliary voltage E_g may still block the gaseous discharge tube II, the unfiltered and therefore steep execution impulse will be caused to result in the steep wave fronts. The discharged energy is then utilized in the load circuit L to synchronize the system in any of the manners well known to the art.

Having described my invention, what I claim as new and desire to secure by Letters Patent is:

1. In a television system, the method of synchronizing a television receiver which includes the steps of receiving line synchronizing signals of predetermined time duration transmitted sequentially with frame synchronizing signals having a time duration greater than that of the said line signals, said frame signals being spaced from said line signals in time duration by a signal-free interval large compared with the time interval between said line signals and large compared with the duration of the said frame signal, preparing for the generation of a synchronizing impulse during the duration of the space between said line and frame signals, and initiating the generation of the said impulse with the commencement of the frame synchronizing signal.

2. A synchronizing system for a television receiver comprising means for receiving line synchronizing signals of predetermined time duration transmitted sequentially with frame synchronizing signals having a time duration greater than those of said line signals and spaced from said line signals by a time interval greater than the time interval between successive line signals and greater than the time duration of said frame signals, means for preparing for the generation of a synchronizing impulse during the duration of the space between said line and frame signals, and means for initiating the generation of the said impulse with the commencement of the frame synchronizing signal.

3. A television receiver synchronizing system comprising means to receive sequentially transmitted line and frame synchronizing signals, means for transmitting a portion of the received signals through a network including a filter to produce a filtered frame signal, means including the filtered frame signal for preparing for the generation of a synchronizing impulse, and means for initiating the generation of the synchronizing impulse by an unfiltered portion of the received signals.

RUDOLF URTEL.
